UNITED STATES PATENT OFFICE.

CHARLES E. OLDACRE, OF TORONTO, ONTARIO, CANADA, ASSIGNOR TO THE GURNEY HEATER MANUFACTURING COMPANY, INCORPORATED, OF BOSTON, MASSACHUSETTS, A CORPORATION OF MASSACHUSETTS.

BOILER.

Application filed November 19, 1925. Serial No. 70,035.

This invention relates to boilers, and particularly to boilers and furnaces adapted for heating purposes.

It is the object of the present invention to provide improvements in boilers and furnaces of the type described in Patent No. 1,326,621, issued to C. B. Thompson in which the gases are caused to pass from the cooler through the hotter strata of the fuel bed before being permitted to escape through the chimney.

With this object in view, the various features of the invention have to do with the adjustment of the furnace to different kinds of coal and fuel beds of various dimensions; with arrangements to facilitate the cleaning of the boiler sections; with an improved adjusting arrangement for the grate bars, and other improvements, the nature of which will more clearly appear from the following detailed description of a preferred embodiment and the appended claims.

The drawings illustrate the invention as applied to the structure disclosed in said patent to C. B. Thompson, only so much being shown as is necessary for a clear understanding of the invention. Fig. 1 is a vertical cross-section of the boiler and furnace; Fig. 2 a front elevation of the water-front adjusting mechanism; Fig. 2^b details of the adjusting mechanism; Fig. 3 a sectional plan view on lines 3—3 of Fig. 1; and Figs. 4 to 6 are various views illustrating the grate-bar lock.

The boiler and furnace parts 1 and 2 are joined together in any suitable manner, e. g., by means of flanges 3^a. The boiler part consists of a desired number of sections 3 and end sections 26 and 27. Preferably, the arrangement of these sections is the same as described in said patent to Thompson. These sections are bounded by ribs, such as 4, which extend around the sections except where openings are provided, thus forming the usual flues for gases between adjacent sections. In the front at the lower side portion of each boiler section, I provide a plurality of louvres 5 opening into the furnace part. These louvres are inclined towards the fire 6 to prevent the dropping of coal into the boiler sections and still allow free

access of the heated gases to the flues. As indicated at 8, the top louvre is closed. With this louvre open, the draft has a tendency to short-circuit therethrough back to 55 the green coalbed 9. Furthermore, with a low fuel supply in the furnace, this louvre, if open to draft, would tend to cool the heating surface of the boiler.

A flue rib or baffle 10 projects from the 60 outer rib 4 of each boiler section at a point near the top louvre 5. The end of baffle 10 is curved down, preferably below the lowermost louvre. The upper part of the baffle 10 extends substantially in a horizontal line 65 so as to provide a large enclosure back of the louvres in which, by the curved lip of the baffle, a whirlpool action of the gases is caused to take place. The horizontal part of baffle 10 may be cleaned from the side of 70 the boiler through opening 11. The end of baffle 10 is so shaped that no soot will deposit thereon, but will fall past it to the bottom of the flue where the cleaning may be effected through side opening 12. The 75 openings 11 and 12 are, of course, covered with removable iron plates on the side 12^a of the boiler (not shown).

Above the baffle 10 a baffle 13 projects from the rib 4. The baffle 13 is upwardly 80 inclined so as to direct the gases of combustion in a curved path towards the flue outlet 14. The even circulation of the gases towards this point is aided also by the sloping contour of the lower part of the flue, 85 which prevents the formation of dead pockets. The air chambers 15 and 16 formed between the sloping part of rib 4 and the outer casing of the boiler 1, serve also to heat insulate the gases flowing through the lower 90 part of the flue. Furthermore, the inclined surfaces tend to concentrate the soot at the bottom of the flue where the cleaning may be readily effected through the side opening. In order to permit cleaning of the necessary 95 area of baffle 13 an L-shaped opening 17 is provided to which access may be had through the side of the boiler. The openings 11, 12 and 17 serve also as passageways 100 between the flues for the gases of combustion. The outlet 14, which is large enough to serve a number of flues, communicates

with chimney flue 18 under the control of the usual damper 19 provided in the outlet collar 20.

The usual connections, including hubs 21 and 22, are provided for permitting the free internal circulation of steam and water in all the boiler sections which are suitably joined together by means of flanges 23.

The furnace part 2 is enclosed within a front wall 24, a top 25, side walls 35, and end sections 26 and 27 (Fig. 2) which are integral extensions of the boiler end sections. The customary magazine charge door 28, slicer or clinker door 29 and ash pit door 30 are provided in the top and front walls, respectively. The end sections 26 and 27 extend only to the grates of the furnace, and below that point the ash pit is covered by plates such as 31 in which air openings such as 32 are provided.

The arrangement of the furnace differs from the one described in said patent to Thompson mainly in the adjusting mechanism of the water front 33. The water front acts as the front wall of the furnace magazine. Water outlet pipes 34 provided at each side of the upper end of water front 33 project through the furnace side walls. The water front 33 is connected through pipes (not shown) with the water space of the boiler 1, thus forming the circulating connection of the boiler. Water is admitted to the water front 33 through pipe 36 projecting through an elongated aperture 37 in the side plate 35.

As shown in Fig. 3, if the number of boiler sections 3 is so great that more than one water front is required to fill up the front space of the furnace 2, then a second water front 33^a is joined to 33 by means of flanges 70. Water circulates from between these two waterfronts through pipes 71.

The water front 33 may be rotated around the pivot constituted by outlet pipes 34 to vary the adjustment of the furnace magazine for various types of coal. The forked end 38 of an arm 39 and the end of an arm 40 are pivotally held together by means of a pin 41 and bear against the water front 33. A horizontal rod 42, held by means of nuts 43 in the end plates 35, carries two sleeves 44 and 45 on which the ends of arms 39 and 40 are pivotally mounted at 46 and 47. The arms 39 and 40 provide a rigid support for the water front 33, relieving stress on the water pipes and, depending on the positioning of sleeves 44 and 45 on rod 42, the water front may be tilted back and forth by means of these arms. Set screws 48 and 49 projecting through the sleeves serve to maintain the latter in their desired positions. The screws 48 and 49 are accessible through the clinker door 29.

A plate 50, mounted on the water front 33, extends to the top 25 of the furnace.

The length of this plate is somewhat less than that of the furnace or water front. Owing to this arrangement air may freely circulate from the openings 32 through the grates 51, and then directly to the ignited layer 6 of coal, and also in front of water compartment 33, on the two sides of plate 50 and down through the green coal 9. The air will thus carry with it any otherwise unconsumed products of combustion down through the most active part of the fire. The plate 50 serves also to prevent coal from falling within the front part of the furnace.

The grate bars 51 are supported on bosses 52 projecting from the furnace front 24 and bosses 53 on the boiler sections. The front end of each grate bar is opposite an aperture 54 provided in the front plate 24, the apertures being normally covered by discs such as 55 pivotally mounted on plate 24 above the apertures. The front ends of the grate bars are flattened on the top as indicated at 56. This flattened portion is slotted at 57 and the slot communicates with an axial cavity 58 in the grate bar end. Normally (see Figs. 4 and 5), the head of an L-shaped latch 59 pivotally mounted on an inside boss 60 of plate 24, projects within slot 57, preventing the rotation of the grate bar. Since the locking means 59 is provided inside of the front plate 24, the grate bars cannot be unlocked through inadvertence.

When it is desired to shake a grate bar, the disc 55 is pushed to one side and the end of a handle is inserted through aperture 54. The end of handle 61 registers with cavity 58 in the grate bar and carries a lug 62 which registers with the slot 57. Therefore, as the handle end is pushed within cavity 58, the lug 62 will tilt latch 59 upward and out of the slot 57. The grate bar may now be shaken, lug 62 preventing the latch 59 from dropping in the slot 57 (see Figs. 3 and 6). When the handle 61 is withdrawn, the latch 59 will drop in the slot 57 and disc 54 will return to its normal position.

While the invention is particularly adapted for use in combination with the boiler herein disclosed, it will be obvious to those skilled in the art that some or all of its features are applicable also to other types of boilers and furnaces without departing from the spirit thereof.

What I claim is:

1. In a furnace, a fuel magazine, a pivotally mounted water front therein, a bar rigidly supported in said furnace, an arm having one end engaging said water front, a pivotal connection for the other end of said arm slidably carried by said bar and means for holding said arm against the said water front for supporting the same.

2. In a furnace, a fuel magazine, a water front in said magazine, a water outlet pipe

leading to said water front and constituting a pivotal mounting for said water front, a bar rigidly supported in said furnace, two pivotally interconnected arms at one end 5 and engaging said water front, pivotal mountings for the other ends of said arms slidably supported on said bar and adjust-

able means for preventing sliding of said mountings on said bar.

In testimony whereof, I have signed my 10 name to this specification, this 14th day of November, 1925.

CHARLES E. OLDACRE.
